of Delaware

Application August 16, 1952, Serial No. 304,773

6 Claims. (Cl. 62—5)

1

The present invention relates to refrigeration and more particularly to refrigeration apparatus for maintaining the desired temperatures in the separate freezing and food storage compartments of a refrigerator cabinet.

Refrigerators usually comprise a high temperature food storage space which should be maintained at a cooling temperature above freezing and a freezing compartment which should be maintained at a low temperature below freezing. In accordance with a recent trend the low temperature compartment is insulated from the food storage space to insure a constant low temperature for storing frozen foods over a long period of time. To maintain these separate compartments at different and substantially constant temperatures with the same refrigeration system presents a difficult problem because of variations in load conditions.

The varying load conditions comprise variations in the ambient temperature from day to day, variations in the relative amounts of foods stored in the freezing and food storage compartments, and variations in the normal use of the refrigerator at different periods during a day and the relative use of the two compartments. The evaporator may be constructed in separate sections for the separate compartments and connected in series for the continuous flow of refrigerant therethrough. If the heat transfer surfaces of the different sections are designed for the worst operating condition, the load on the two sections can be properly balanced for that condition. However, under a more favorable operating condition the low temperature section will produce the desired temperature in the freezing compartment with less refrigerant and deliver more refrigerant to the high temperature section which may result in a freezing temperature in the food storage compartment and the formation of frost on the heat transfer surface.

In another of my applications for United States Letters Patent filed concurrently herewith a refrigeration apparatus is illustrated in which refrigerant overflowing from a low temperature evaporator section enters a drain conduit bypassing a high temperature evaporator section. Liquid refrigerant is fed from a liquid trap in the drain conduit to the top of the high temperature evaporator section by a vapor liquid-lift. The vapor liquid-lift is operated by a heater controlled by a thermostat responsive to a high temperature condition affected by the high temperature evaporator section to deliver refrigerant to the latter as required.

2

One of the objects of the present invention is to provide a refrigerator having separate low and high temperature compartments with a refrigeration apparatus having a novel construction for balancing the load in the separate compartments under all operating conditions.

Another object is to provide a refrigeration apparatus for normally delivering refrigerant from the outlet of a low temperature evaporator section to the inlet of a high temperature evaporator section and diverting the refrigerant through a bypass around the high temperature evaporator section upon the occurrence of a low temperature condition affected by the latter.

Still another object is to provide a refrigeration apparatus of the type indicated with a refrigerant feed conduit between the low and high temperature evaporator sections through which liquid refrigerant flows by gravity and a heat operated device in the feed conduit for producing a vapor lock therein to divert refrigerant through a drain conduit around the high temperature section.

These and other objects will become more apparent from the following description and drawing in which like reference characters denote like parts throughout the several views. It is to be expressly understood, however, that the drawing is for the purpose of illustration only and not a definition of the limits of the invention, reference being had for this purpose to the appended claims. In the drawing:

The figure is a diagrammatic view of an absorption refrigeration system incorporating the novel features of the present invention and showing the heat operated device in the feed conduit for controlling the flow of refrigerant to and around the high temperature evaporator section.

For purposes of illustration the present invention is shown applied to a refrigerator comprising a cabinet 3 providing a food storage space 4 adapted to be cooled to some temperature above freezing and having a freezing compartment 5 therein insulated from the space 4 by walls 6. It will be understood that the cabinet 3 may have the food storage compartment 4 completely separated from the freezing compartment 5 with separate closures at the outside of the cabinet. The interior of the refrigerator cabinet 3 is refrigerated by a cooling element or evaporator 7 having a low temperature section 7a to maintain a substantially constant temperature in the freezing compartment 5 and a separate high temperature section 7b to maintain a substantially

constant temperature above freezing in the food storage space 4.

Evaporator 7 constitutes one element of a single mechanical refrigeration system and for purposes of illustration is shown applied to a three-fluid absorption refrigeration system generally similar to that illustrated and described in United States Letters Patent to Alvar Lening 2,300,579, issued November 3, 1942, and entitled Refrigeration. Such a refrigeration system comprises a refrigerant circuit for delivering liquid refrigerant to evaporator 7, a gas circuit for delivering an inert gas to the evaporator in which the refrigerant evaporates and diffuses at partial pressure to produce a refrigerating effect, and an absorption solution circuit in which an absorbent is circulated to absorb refrigerant from the gas and from which refrigerant vapor is expelled by the application of heat. The absorption refrigeration system illustrated comprises a generator 8, a condenser 9, the evaporator 7, a gas heat exchanger 10, an absorber 11 and a liquid heat exchanger 12 interconnected for the circulation of refrigerant, absorbent, and the auxiliary pressure equalizing gas.

Generator 8 is in the form of an upright cylindrical vessel having a central or axial flue 13 providing an annular chamber 14 therebetween for absorption solution. Flue 13 is heated by radiant heat and the products of combustion from a fuel burner 15. The top of the annular chamber 14 of generator 8 is connected to the upper end of the condenser 9 by a vapor pipe 16.

Condenser 9 is preferably air cooled and as illustrated comprises a vertically arranged serpentine coil having spaced heat transfer fins 17. The lower or outlet end of condenser 9 is connected to the top of the low temperature evaporator section 7a by a conduit 18.

The evaporator 7 is located in the cabinet 3 to be refrigerated and the remainder of the apparatus is generally located at the exterior of the cabinet. Low temperature evaporator section 7a comprises a section of pipe bent to generally conform to the shape of the interior of the freezing compartment 5 in which it is located but progressively inclined from the top to the bottom so that liquid refrigerant will flow therethrough by gravity. The high temperature section 7b of the evaporator is illustrated in the form of a vertically arranged serpentine coil located in the food storage space 4 and having heat transfer fins 19. The lower end of the low temperature section 7a is connected to the upper end of the high temperature section 7b by a connecting section 7c to provide a continuous path for the flow of gas through the evaporator. Liquid refrigerant, however, is drained from the bottom of the low temperature section 7a and fed to the top of the high temperature section 7b by means later to be described in detail. The lower or outlet end of the high temperature evaporator section 7b is connected by a conduit 20 to one end of chamber 21 of gas heat exchanger 10 constituting one path of flow for the inert pressure balancing gas.

The gas heat exchanger 10 is formed by a cylindrical shell 22 having closed ends and spaced tube sheets 23 and 24 therein provide the chamber 21 therebetween. Tubes 25 extend through the chamber 21 between the tube sheets 23 and 24. The space between the tube sheets 23 and 24 and the ends of shell 22 constitute headers

26 and 27 which together with the tubes 25 constitutes a second path of flow for the pressure balancing inert gas in heat exchange with the gas in chamber 21. A conduit 28 depends from the end of chamber 21 of gas heat exchanger 10 opposite from the end connected to evaporator 7 and is connected to the lower end 29 of absorber 11.

Absorber 11 is also illustrated in the form of a vertically arranged serpentine coil and its upper end 30 is connected to header 26 of gas heat exchanger 10. The opposite header 27 of gas heat exchanger 10 is connected by a conduit 31 to the top of the low temperature evaporator section 7a. The lower end of depending conduit 28 extends beyond its connection to the absorber coil and is connected to the top of an absorber pot 33 and the bottom of the absorber pot is connected to the generator 8 by a conduit 34.

Conduit 34 constitutes the inner passage of liquid heat exchanger 12 and a vapor liquid-lift 35. The lift 35 comprises several turns 35a of conduit 34 wound around a depending portion 13a of flue 13 and an upright portion 35b having its upper end connected to chamber 14 of generator 8 adjacent the top thereof. Surrounding the conduit 34 is a sleeve 36 constituting a second passage 37 of liquid heat exchanger 12. A pipe 38 connects the lower end of generator chamber 14 to one end of the outer sleeve 36 and the opposite end of the sleeve is connected to the upper end or top of the absorber 11 by a riser 39. As illustrated, riser 39 has a hairpin bend with heat transfer fins 40 thereon.

Heat from fuel burner 15 is transferred through the wall of the flue 13 to the solution in chamber 14 to expel refrigerant vapor therefrom. The refrigerant vapor flows through vapor pipe 16 to condenser 9 where it is condensed to a liquid and the liquid refrigerant flows by gravity through the conduit means 18 to the top of the low temperature evaporator section 7a. The liquid refrigerant flowing downwardly through evaporator 7 by gravity evaporates and diffuses into the pressure equalized gas at partial pressure to produce a refrigerating effect and the heavier mixture of refrigerant and gas flows downwardly into the chamber 21 of the gas heat exchanger 10. Gas laden with refrigerant vapor then flows through the chamber 21 in heat exchange relation with the gas weak in refrigerant flowing from the absorber through the tubes 25 of gas heat exchanger 10 and then through conduit 28 into the bottom of the absorber 11.

Simultaneously absorption solution weak in refrigerant flows by gravity from the chamber 14 of generator 8 to the top of absorber 11 in a path of flow comprising the pipe 38, outer passage 37 of liquid heat exchanger 12 and conduit 39. Absorption solution flowing downwardly through the absorber 11 absorbs refrigerant vapor from the inert gas in which it is diffused and the lighter gas tends to rise and flow upwardly through the absorber to the header 26 of the gas heat exchanger 10, then through the tubes 25 to the header 27 and from the header through the conduit 31 to the top of the evaporator 7. Thus, circulation of the pressure equalizing gas is initiated by the differential weights of columns of gas strong in refrigerant and gas weak in refrigerant in the gas circuit.

Absorption solution rich in refrigerant flows from the lower end of absorber 11 into the absorber pot 33 and from the latter through the

conduit 34. The absorption solution in the coils 35a surrounding the depending extension 13a of flue 13 is heated to expel refrigerant vapor and the expelled vapor lifts the solution through the upright portion 35b of conduit 34 into the top of the chamber 14 of generator 8 for gravity flow through the absorption solution circuit. As thus far described the absorption refrigeration system is substantially identical with that illustrated and described in the Lenning patent, referred to above, except for the particular construction and arrangement of the separate evaporator sections 7a and 7b.

In accordance with the present invention the refrigeration system delivers all of the refrigerant liquefied in the condenser 9 to the top of the low temperature evaporator section 7a of evaporator 7 for gravity flow therethrough to insure an adequate supply of refrigerant to maintain the desired low temperature in the freezing compartment 5. Surplus refrigerant overflowing from the bottom of the low temperature evaporator section 7a enters a feed conduit 45 connected to the top or inlet end of the high temperature evaporator section 7b for gravity flow therethrough. A heat operated device 46 is provided in the feed conduit 45 for producing a vapor lock therein to stop the flow of refrigerant to the high temperature evaporator section 7b and divert the refrigerant through an overflow drain conduit 47 bypassing the latter section. Operation of the refrigeration system is controlled by a thermostat 48 responsive to a temperature condition affected by the low temperature evaporation section 7a and operation of the heat operated device 46 is controlled by a second thermostat 49 responsive to a temperature condition affected by the high temperature evaporator section 7b to regulate the supply of liquid refrigerant to each of the separate evaporator sections as required.

The feed conduit 45 comprises a depending pipe 50 having its upper end connected to the lower or outlet end of the low temperature evaporator section 7a and its opposite end connected to the side of a vessel 51 adjacent the bottom thereof. The vessel may have other shapes but as illustrated is in the form of a bottle having an upper reduced neck portion 52. A U-shaped pipe 53 has one end 54 projecting upwardly through the bottom of the vessel 51 to a level above the connection of the pipe 50 therewith, and its opposite end 55 connected to the upper or inlet end of the high temperature evaporator section 7b. It will be noted that the vessel 51 is located below the top or inlet end of the high temperature evaporator section 7b and that the bight portion of the U-shaped pipe 53 depends below the vessel 51. Thus, liquid refrigerant overflowing from the outlet end of the low temperature evaporator section 7a flows through the pipe 50 to the vessel 51 and fills the latter and the U-shaped pipe 53 to a level at which the liquid refrigerant will overflow into the high temperature evaporator section 7b.

The heat operated device 46 for regulating flow through the feed conduit 45 is illustrated in the form of an electric heating element 56 in thermal contact with the reduced neck portion 52 of the vessel 51. The electric heating element 56 is connected to a source of electric current such as an electric power line 57. Electric heating element 56 when energized vaporizes a portion of the refrigerant therein to produce a vapor lock in the vessel 51 above the upwardly projecting end 54 of the U-shaped pipe 53 to prevent flow

of liquid through the latter and cause it to back up in the depending pipe 50 and overflow through the drain conduit 47 bypassing the high temperature evaporator section 7b.

The overflow drain conduit 47 comprises a pipe connected between outlet end of the low temperature evaporator section 7a and the outlet end of the high temperature evaporator section 7b and a branch 47a connected to the pipe 50 above the outlet end 55 of the feed conduit 45. The branch 47a and depending portion of conduit 47 bypass the high temperature evaporator section 7b and the portion of conduit 47 above the branch constitutes a vent. It will be noted that the depending U-shaped pipe 53 of feed conduit 45 produces a liquid column of a height h to balance the liquid column h' in the pipe 50, at which level the refrigerant overflows through the branch 47a of bypass drain conduit 47. To prevent the liquid trap in the U-shaped pipe 53 from being blown when the heating element 56 is energized, a vent pipe 58 is connected between the top of the reduced neck portion of vessel 51 to the section 7c between the high and low temperature sections. The vent pipe 58 may be of such dimensions as to restrict the flow of vapor therethrough or may have an orifice therein to limit the vapor flow which will vary in direct proportion to the height of the liquid column h and h' .

Thermostat 48 for controlling operation of the refrigeration system may be of any suitable construction for operating a gas valve 59 to regulate the supply of fuel to the burner 15 responsive to a temperature condition affected by the low temperature evaporator section 7a. As illustrated diagrammatically, the thermostat comprises a bulb 60 so located as to be subjected to the temperature in the freezing compartment 5, a bellows 61 connected to actuate the gas valve 59 and a tube 62 connecting the bulb and bellows. The bulb 60, tube 62 and bellows 61 contain a fluid for actuating the bellows upon changes in temperature in the freezing compartment 5 to regulate the amount of gas supplied to burner 15 in accordance with requirements to maintain a substantially constant temperature in the freezing compartment.

The second thermostat 49 controls the heating element 56 of the heat operated device 46 and also may be of any suitable construction to energize the heating element in response to a predetermined low temperature condition affected by the high temperature evaporator section 7b. The thermostat 49 comprises a bulb 63 so located in cabinet 3 as to be responsive to the food storage space 4, a bellows 64 and a tube 65 connecting the bulb and bellows. Bellows 64 is connected to actuate an electric switch 66 in one side of the power line 57 connected to the electric heating element 56. The bulb 63, bellows 64 and tube 65 of thermostat 49 contain a fluid for actuating the switch 66 to closed position at a predetermined low temperature in the food storage space 4 and open the switch at any temperature above the predetermined low temperature. One form of the invention having now been described in detail, the mode of operation is explained as follows.

For purposes of description let it be assumed that the freezing compartment 5 is above the desired temperature and that thermostat 48 has opened gas valve 59 to supply fuel to burner 15. Heat from the gas burner 15 expels refrigerant vapor from absorption solution in the generator 8 and vapor and absorption solution are delivered to the condenser 9 and absorber 11, respec-

tively. Refrigerant liquefied in the condenser 7 flows through the feed conduit 18 to the top of the low temperature evaporator section 1a of the evaporator 7 and the refrigerant flows by gravity from the top to the bottom of the evaporator section. Simultaneously, inert gas weak in refrigerant flows into the top of the low temperature evaporator section 1a and the liquid refrigerant evaporates and diffuses into the inert gas at a partial pressure and low temperature to produce a refrigerating effect. If the freezing compartment 5 is at a relatively high temperature, the amount of heat transmitted through the walls of the low temperature evaporator section 1a will vaporize all of the liquid refrigerant as it flows therethrough. As the temperature in the freezing compartment 5 decreases, however, the amount of heat transmitted will decrease and the evaporator section is designed to produce and hold the freezing temperature desired when evaporating only a portion of the refrigerant flowing therethrough. Surplus liquid refrigerant at the outlet end of the low temperature evaporator section 1a flows through the feed conduit 45 comprising the depending pipe 50, vessel 51 and U-shaped pipe 53 into the upper or inlet end of the high temperature evaporator section 7b. The refrigerant fills the depending bight portion of the U-shaped pipe 53 and vessel 51 above the outlet end 55 of pipe 53 and below the overflow branch 47a of drain pipe 47. The liquid refrigerant then flows by gravity through the high temperature evaporator section 7b. Simultaneously, gas from the low temperature section 1a flows through the connecting portion 7c of the evaporator to the high temperature section 7b. The liquid refrigerant then evaporates and diffuses into the gas in the manner as previously explained with respect to the low temperature section 1a but at a higher partial pressure and temperature to produce a refrigerating effect in the food storage space 4.

When the temperature in the food storage space 4 decreases below a predetermined low temperature, for example 38° F., the thermostat 49 operates to close the electric switch 66 and thereby energize the heating element 56. Heat from the heating element is transmitted through the neck portions 52 of the vessel 51 and vaporizes a portion of the liquid refrigerant therein. As the amount of refrigerant vaporized and the pressure of the vapor increases due to the continuous transfer of heat from the heating element 56, the liquid level in the vessel 51 is depressed below the upwardly projecting end 54 of the U-shaped pipe 53 therein and thereby stops the flow of refrigerant to the high temperature evaporator section 7b. The vapor pressure in vessel 51 causes the liquid refrigerant to back out through the pipe 50 until it overflows through branch 47a of drain conduit 47 and bypasses the high temperature evaporator section 7b. Simultaneously, the liquid level is depressed in the upright end 54 of the U-shaped conduit 53 to produce a liquid column h therein which balances the liquid column h' in the conduit 50 so that all of the additional refrigerant supplied from the low temperature section 1a will flow through the overflow drain conduit 47 and bypass the high temperature evaporator section 7b. Refrigerant vapor in the reduced neck portion 52 of vessel 51 continuously flows at a predetermined rate through the restricting vent pipe 58 and the rate of flow through the vent varies

in direct proportion to the height of the liquid columns h and h' and the capacity of the heating element 56, size of the restricting vent pipe 58 and height of the U-shaped pipe 53 are so designed as to produce an equilibrium condition before the liquid trap blows in the U-shaped pipe 53. The apparatus continues to operate with no refrigerant being supplied to the high temperature evaporator section 7b until the temperature in the food storage space 4 increases to a degree at which the thermostat 49 opens the switch 66. Liquid refrigerant flowing from the low temperature section 1a then feeds directly into the high temperature section 7b as previously explained. Thus, the apparatus operates to supply liquid refrigerant to the low temperature evaporator section 1a in sufficient quantities to insure the desired low temperature in the freezing compartment 5 and supplies refrigerant to the high temperature evaporator section 7b as required to maintain the desired temperature in the food storage space 4. With the arrangement of elements described above, all of the refrigerant is available for use when either of the compartments is calling for refrigeration and refrigerant is vaporized to stop the flow of refrigerant to the high temperature compartment only when the food storage space 4 is below a minimum temperature.

It will now be observed that the present invention provides a refrigeration system having separate freezing and food storage compartments with a refrigeration apparatus for balancing the load in the separate compartments under all operating conditions. It will also be observed that the present invention provides an arrangement for feeding liquid refrigerant from the low temperature evaporator section directly to the high temperature evaporator section so long as the food storage compartment is above a predetermined low temperature and diverting such refrigerant through a bypass around the high temperature evaporator section upon the occurrence of the predetermined low temperature in the food storage space. It will also be observed that the present invention provides a heat operated device in the feed conduit between the low and high temperature evaporator sections which is operative to produce a vapor lock and divert refrigerant through a bypass around the high temperature section.

While a single embodiment of the invention is herein illustrated and described, it will be understood that modifications may be made in the construction and arrangement of elements without departing from the spirit or scope of the invention. Therefore, without limitation in this respect, the invention is defined by the following claims.

I claim:

1. In a refrigerator, a cabinet having separate compartments, a refrigeration system comprising an evaporator having a low temperature section and a high temperature section in the separate compartments of the cabinet, each of said sections being arranged for the gravity flow of refrigerant therethrough, a refrigerant liquefier in the system connected to deliver refrigerant to the top of the low temperature evaporator section, a feed conduit connecting the bottom of the low temperature section to the top of the high temperature section through which liquid refrigerant flows by gravity, an overflow drain pipe connected between the feed conduit and the outlet from the high temperature section for bypassing

the latter, the point of connection of said feed conduit with the overflow drain pipe being located above its point of connection with the high temperature section, a heat operated device in the feed conduit for stopping the flow of refrigerant therethrough to cause it to bypass the high temperature evaporator section through the overflow drain pipe, and a control responsive to a temperature condition affected by the high temperature evaporator section for operating the heat operated device.

2. A refrigeration system in accordance with claim 1 in which the heat operated device is a vapor trap in the feed conduit and an electric heating element in thermal contact with the vapor trap for vaporizing refrigerant.

3. A refrigeration system in accordance with claim 1 in which the feed conduit comprises a liquid trap, the heat operated device comprises a vapor trap in the liquid trap and an electric circuit having a heating element in thermal contact with the vapor trap, and the control comprises a thermostatically operated switch in the electric circuit.

4. In a refrigeration system in accordance with claim 1 in which the feed conduit comprises a depending U-shaped liquid trap, the overflow drain pipe, being connected to the feed conduit above the outlet connection of the latter with the top of the high temperature evaporator section, and the heat operated device comprises a vapor trap in the U-shaped liquid trap and a heating element in thermal contact with the vapor trap.

5. In a refrigeration system in accordance with claim 1 in which the feed conduit comprises a vessel, a depending pipe connecting the outlet end of the low temperature evaporator section to the vessel, a depending U-shaped pipe con-

necting the vessel to the top of the high temperature evaporator section, the overflow drain pipe being connected to the depending pipe above the connection of the depending U-shaped pipe with the high temperature evaporator section, said depending U-shaped pipe having a riser of greater height than the height of the feed conduit below the overflow drain pipe, and the heat operated device comprising an electric heating element in thermal contact with the vessel above the connection of either pipe therewith.

6. In a refrigeration system in accordance with claim 1 in which the feed conduit comprises a pipe depending from the outlet end of the low temperature evaporator section, a vessel having an upper restricted neck portion and a depending U-shaped pipe having one end projecting upwardly through the bottom of the vessel above the connection of the depending pipe therewith and its opposite end connected to the top of the high temperature evaporator section, the overflow drain pipe being connected to the depending pipe above the connection of the depending U-shaped pipe with the high temperature evaporator section, a restricting vent pipe connecting the top of the vessel to the high temperature evaporator section, an electric circuit having a heating element surrounding the reduced neck portion of the vessel, and the control comprising a thermostatic switch in the electric circuit.

WILLIAM R. HAINSWORTH.
